DATA PROCESSING CONTROL UNIT

Thomas A. Molyneaux, Waterford Township, Oakland County, Mich., assignor to Emerson Electric Co., St. Louis, Mo.

Filed Sept. 30, 1971, Ser. No. 185,044

Term of patent 14 years

Int. Cl. D14—02

U.S. Cl. D26—5 C

FIG. 1.

FIG. 2.

FIG. 3.

FIG. 4.

FIG. 1 is a perspective view taken from the top, front and right side of a data processing control unit embodying my new design;

FIG. 2 is a front elevational thereof, the rear being plain and unornamented;

FIG. 3 is a left side elevation thereof; and

FIG. 4 is a top plan view thereof, with the telephone receiver omitted for convenience of illustration.

I claim:

The ornamental design for a data processing control unit, as shown and described.
